(57) **CLAIM**

The hanging member with nut, as shown and described.

DESCRIPTION

FIG. 1 is a front view of a first embodiment of a hanging member with nut;

FIG. 2 is a top view side view thereof;

FIG. 3 is a bottom edge view thereof;

FIG. 4 is a left side view thereof;

FIG. 5 is a right view thereof;

FIG. 6 is an isometric view thereof; and

FIG. 7 is a front view of a second embodiment of the hanging member with nut;

FIG. 8 is a top view side view thereof;

FIG. 9 is a bottom edge view thereof;

FIG. 10 is a left side view thereof;

FIG. 11 is a right view thereof; and,

FIG. 12 is an isometric view thereof.

The feature drawn in broken lines in FIGS. 1-3, 5, 6-9, 11 and 12 show an unclaimed threaded shaft.

1 Claim, 4 Drawing Sheets(56)
